PUSH-PULL AMPLIFIER

Popko Reinder Dyksterhuis, Eindhoven, Netherlands, assignor to Radio Corporation of America, a corporation of Delaware

Application August 30, 1930, Serial No. 478,831,
and in the Netherlands September 2, 1929

9 Claims. (Cl. 179—171)

The present invention relates to amplifiers, and more particularly to improvements in, or relating to, circuit arrangements for push-pull amplifiers.

5 This invention has reference to push-pull amplifiers, and has for its main object to provide a circuit arrangement that permits in a simple manner the controlling of the intensity, and of adjusting the balance.

10 According to this invention, for the purpose, the cathodes and the negative terminal of the source of anode current have interconnected between them a resistance consisting of one or more parts and traversed by the anode direct current, a variable point of the said resistance being connected to the cathode, and at least one of the grids being connected to a second variable point.

15 The novel features which I believe to be characteristic of my invention are set forth in particularity in the appended claims, the invention itself, however, as to both its organization and method of operation will best be understood by reference to the following description taken in connection with the drawing in which I have indicated diagrammatically one circuit arrangement whereby my invention may be carried into effect.

20 Referring to the single figure, 1 and 2 designate triodes connected in push-pull in the usual manner. The grids 15 are supplied from transformers 3 and 4, which, in reality, are not necessarily separated, as shown in the figure, but which may form a single push-pull transformer as well known to those skilled in the prior art. The secondary windings 3', 4' of transformers 3 and 4 are connected to the cathodes 14 through condensers 16 and 17. The cathodes 14 are, in addition, connected through resistances 8 and 5 to the negative terminal of the source of anode current.

25 A sliding contact 9 permits the short-circuiting of part of the resistance 8. It is thus possible to give the grid bias any desired value. The secondary windings of the transformers 3 and 4 are connected through resistances, or inductances, 13 and 12 respectively to the points 7 and 6 of the resistance 5. In the figure, the point 7 is to be considered variable, whereas the point 6 is to be assumed stationary.

30 The function of the latter arrangement is to permit compensation for any disparity in the two triodes, since if no particular means are taken it often occurs that the direct current of the two triodes of a push-pull circuit arrange-

ment is different. By slightly shifting the sliding contact 7 the direct current in one triode can be equalized in a simple manner with that in the other, an exact push-pull connection being thus ensured. It is possible to test the uniformity of the direct current in the two triodes for example by including a milliammeter in each of the two anode circuits.

35 The negative terminal of the anode current source and the sliding contact 7 have interconnected between them a high resistance 11. The latter ensures that if at a given moment the sliding contact 7 does not make contact with the resistance 5, nevertheless the grid of one of the triodes is not insulated, which might give rise to wide undesired potential variations.

40 It is, of course, obvious that the point 6 may be variable. In this case it is necessary to interconnect between this point and the negative terminal of the anode current source a high resistance having the same function as the resistance 11. The resistances, or inductances, 12, 13 and the condensers 16 and 17 are particularly important if the anode current is supplied from a high tension unit. In this case the said elements act as filters, and annul any alternating voltages that may still occur and give rise to humming.

45 The resistance 8 is, likewise, connected in such a manner that when the sliding contact 9 happens to make no contact with the resistance 8 the connection between the source of anode current and the cathode 14 is not interrupted. It is, of course, obvious that the resistances 5 and 8 are not necessarily separated, but may be combined to form a single unit. The anodes of the tubes 1, 2 are connected, in any well known manner to a utilization circuit.

50 While I have indicated and described one arrangement for carrying my invention into effect, it will be apparent to one skilled in the art that my invention is by no means limited to the particular organization shown and described, but that many modifications in the circuit arrangements, may be made without departing from the scope of my invention as set forth in the appended claims.

55 What I claim is:

1. The combination of current supply means, a push-pull amplifier, a connection between the positive terminal of said means and the anodes of the amplifier, a second connection between the cathodes of the latter and the negative terminal of said means, said second connection including a bias resistor path for the grids of the
